UNITED STATES PATENT OFFICE.

PETER ZUCKRIESEL, OF TELL CITY, INDIANA.

KNOCKDOWN BOOTH.

SPECIFICATION forming part of Letters Patent No. 453,528, dated June 2, 1891.

Application filed May 15, 1890. Serial No. 351,914. (No model.)

To all whom it may concern:

Be it known that I, PETER ZUCKRIESEL, of Tell City, in the county of Perry and State of Indiana, have invented a new and Improved 5 Knockdown Booth, of which the following is a full, clear, and exact description.

My invention relates to an improvement in knockdown booths, and has for its object to provide a series of booths or a single booth 10 especially adapted for use in voting under what is known as the "Australian system."

The object of the invention is to provide a booth which will afford secrecy for the voter, and also to provide a means whereby the 15 booth or booths may be expeditiously knocked down and folded up in a small compass for transportation or for preservation; and a further object of the invention is to so construct the booth or booths that while ample 20 secrecy is afforded the voter the judges of an election may determine, without entering the booth, whether or not it is occupied and also whether it contains more than one person.

The invention consists in the novel construction and combination of the several parts, as will be hereinafter fully set forth, and pointed out in the claims.

Reference is to be had to the accompanying drawings, forming a part of this specification, 25 in which similar figures of reference indicate corresponding parts in all the views.

Figure 1 is a perspective view of a series of connected booths adapted to be suspended from the wall or supported upon the floor, the 35 said booths being constructed in such manner that the lower portion thereof is open. Fig. 2 is a longitudinal section through the folded booths taken on line 2 2 of Fig. 3, and Fig. 3 is an end view of the folded booths. 40 Fig. 4 is a detail side elevation of one of the curtain-poles adapted for use in connection with a series of single booths. Fig. 5 is a perspective view of a slightly-modified form of a group of booths. Fig. 6 is a transverse 45 section taken through the hinged portion of the booth shown in Fig. 5 when folded. Fig. 7 is a perspective view of a single booth. Fig. 8 is a transverse section taken through the hinged portion of the single booth when 50 the same is folded, and Fig. 9 is a detail side elevation of a curtain-pole for use in connection with the connected booths.

That form of booth illustrated in Fig. 1 consists of a back board 10, which may be of any desired length, the length of the said board being ordinarily sufficient to constitute the backs of three (more or less) independent booths. The back board 10, at each end upon its front face, is provided with an integral or attached vertical rib 11, and upon the front 55 edge of each of said ribs a side board 12 is hinged, the thickness of the side boards being essentially equivalent to the width of the inner faces of the ribs 11. Upon the inner face of the back board 10 two intermediate partition-boards 13 and 14 are hinged, which boards are of a width corresponding to the combined width of the side boards and the ribs 11, and the said intermediate partition-boards are so hinged to the back board that they may be 60 folded upon the back board in such manner that the outer edge of each of the said intermediate boards will essentially contact with the inner face of each rib 11. The intermediate partition-boards 13 and 14, and likewise the side boards 12, are of a length corresponding to the width of the back board, and upon the inner face of the back board, at its 65 lower edge, a shelf or desk 15 is rigidly attached, which shelf or desk extends from end to end of the board and is divided into two longitudinal sections *a* and *a'*, which sections are hinged together in such manner that the outer section is capable of folding upward 70 upon the partitions when closed.

To the outer face of each of the side boards 12, near the upper rear corner, the upper end of a leg 16 is pivoted, and each of said legs is provided, preferably, with a thumb-screw 17, adapted to enter the edges of the desk or 75 shelf 15 when the legs are in the vertical position, in which position they tend to support 80 the booth. The legs are about as long again as the length of the side boards and intermediate partitions, and when the booth is 85 folded out for use, as shown in Fig. 1, the side boards and intermediate partitions extend at a right angle outward from the back board, and are held in this position by means of thumb-screws 17^a, passing through the shelf 90 or desk plate 15, as also by a rod 18, which rod is provided with spaced integral or attached pins 19, adapted to enter holes in the 95 upper edges of the said side boards 12 and 100

intermediate partitions 13 and 14. This rod is adapted to act as a curtain pole or rod, and upon it a number of curtains 20 are held to slide corresponding to the number of 5 booths of the set. The curtains are of the same length as the side boards and partitions. Thus when a voter enters either of the booths and draws the curtain he has all the secrecy that the law requires, and the judges of election are enabled by reason of the exposure of the lower portion of the voter's person to know whether or not the booth is occupied and whether more than one person is in the 10 booth without drawing the curtain thereof. 15 If the booths are to be attached to the wall, the legs 16 may be dispensed with and the said booths be suspended by eyes 21, attached to the upper or rear edges of the back board. These eyes may be utilized also to steady the 20 booth, even when it is supported upon the legs 16.

In the form of booth illustrated in Fig. 5 the construction is somewhat different, and consists of three back boards 22, 23, and 24, 25 which back boards are preferably about seven feet in height, more or less. To the inner face of each outer back board 22 and 24 at the outer edge a longitudinal vertical rib 25 is attached, and to each of the ribs 25 a side 30 board 26, of equal length with the back board, is hinged to fold inward. To the inner edge of the back board 22 one rear side face of an intermediate partition 27 is hinged, the opposite rear side face of said partition being provided with an attached or integral longitudinal rib 28, and to the longitudinal edge of this rib the opposed edge of the back board 23 is hinged. The opposite edge of the back board 23 is hinged to the opposed face of the 35 back board 24, and to the inner face of the back board 24 at its inner edge a second intermediate partition 29 is hinged in such manner that when the booth is set up and the partitions extend outward at a right angle to the back the rear edge of the partition 29 will contact with the inner face of the back board 23. A curtain rod or rods 18, similar to that above described in connection with the other form of booth, is provided for 40 this form, and the said curtain-rod is likewise provided with curtains 20. The side boards and intermediate partitions of the booth are of equal length with the back, whereby they may be stood on either end; 45 but the curtains 20 are but half the length of the back, in order that the lower portion of the person of the voter may be exposed.

When the partitions and side boards are folded out for use, a detachable shelf 30 is 50 located in each booth transversely at about the center of it, which shelves are ordinarily made to contact at their ends with the lower walls of upper panels 31, formed in the side boards and partitions, and the rear edge of 55 the shelves is ordinarily made to engage with the back boards, and the said shelves are fastened on each side of the partitions and

side boards by hooks which penetrate the walls of the panels. By this means the partitions and side boards are not dependent 70 upon the curtain-rods for their position.

In the construction of a single booth a back board 32 is provided with a rib 33 upon the inner face at one edge, and to said rib a side board 34 is hinged, the opposite side board 35 being hinged directly to the outer longitudinal edge of the back board. The same form of curtain-rod and curtain is employed in this form of booth as has heretofore been described, and a shelf or desk 30 is likewise used. 80

A single curtain-rod may be employed to extend from end to end of a series of booths, or a rod may be used in connection with each compartment, which rods may be provided with two spaced lugs at each end, as shown in 85 Fig. 4. A number of single booths may be connected to form a series by employing curtain poles or rods 18^a, having two spaced lugs 19 at each end to fit over the tops of the side boards. 90

When the booths shown in Fig. 1 are to be folded up for storage or transportation, the curtain-pole 18 is removed, the partition 13 is then folded in against the back board in the direction of one of the side boards 11, and the partition 14 is folded in the same manner in the direction of the opposite side board. The side boards are then folded in upon the partitions, the legs when used having been previously carried up out of the way, and the 100 said legs are then folded one upon the other longitudinally of the back and in contact with the side boards. The curtain-rods are placed or packed in the hollow formed by the panels, and to provide for ample space the back 105 boards may also be paneled. The section a' of the desk is folded upward, as shown in Figs. 2 and 3.

In that form of booth shown in Fig. 5 the partition 27 is carried outward in the direction of the contiguous side board and folded upon the back board 22 and the side board 26 is folded upon the partition. The back board 23 is then folded upon the side board, the partition 31 is folded upon the back board 24, and both the partition and the back board are folded to contact with the rear face of the back board 23. The remaining side board is then folded down to place, as illustrated in the cross-section, Fig. 6. 110 115 120

It will be observed that when the booth shown in Fig. 5 is folded it is thicker than the folded booth shown in Fig. 2, but not as long.

In folding a single booth the side board 125 hinged directly to the back board is folded upon the inner face of the latter, and the other side board is then folded to contact therewith, as is illustrated in Fig. 8.

When the form of booth shown in Fig. 1, 130 for instance, is to be placed in a school-house, after the election the booths may be folded and hung upon the wall and used as a black-board. This is accomplished by hinging a

board 15^a to the outer edge of the desk 15, having one prepared surface, the said board being of sufficient length to completely cover, or almost so, the front of the folded article, 5 as shown in Fig. 3. When the booth is in use, board 15^a hangs down from the desk, as shown in Fig. 1. The curtains are preferably transparent, or practically so, being usually made of a light fabric having the characteristics of 10 wire-gauze, for instance, enabling the person in the booth to readily observe objects outside, but effectually preventing outside parties from looking through the curtain into the booth.

15 Having thus described my invention, I claim as new and desire to secure by Letters Patent—

1. In a knockdown booth, the combination, with a back, of side boards hinged thereto, 20 and adapted to fold inward, a detachable clamping-rod having depending pins 19 19 to engage the side boards and hold them spaced, a curtain suspended from the rod, the lower half of the booth being open to disclose 25 whether or not it is occupied, substantially as set forth.

2. In a knockdown booth, a back, sides hinged thereto to fold thereagainst, a folding shelf, and a blackboard hinged to the folding 30 shelf to swing over the booth when folded, for the purpose set forth.

3. A knockdown booth, comprising the back 10, having supporting eyes 21, end ribs 11, a series of hinged side boards, a rod having depending pins to engage said side boards 35 and hold them extended, curtains on said rod between the side boards, shelf 15, having a hinged section, legs 16, pivoted at their upper ends to the upper portions of the outer side boards, and set-screws passed through the 40 legs into the ends of the said shelf, substantially as set forth.

4. In a knockdown booth, the combination, with a back board, of a series of partition-boards hinged to the back board and capable 45 of folding thereon and upon each other, a clamping-rod connecting and binding the partitions, and curtains attached to the said rod, substantially as and for the purpose specified. 50

5. In a knockdown booth, the combination, with a back, of partitions hinged to the back and adapted to fold thereon and upon each other, a sectional hinged desk attached to the back beneath the partitions, a clamping-rod 55 engaging with the partitions, and curtains attached to the said rod, substantially as and for the purpose specified.

PETER ZUCKRIEGEL.
